(57) **CLAIM**

The ornamental design for toilet rim blocks, as shown and described.

DESCRIPTION

FIG. 1 is a top perspective view of toilet rim blocks embodying the new design according to a first embodiment;

FIG. 2 is a bottom perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof; and

FIG. 8 is a bottom view thereof.

FIG. 9 is a top perspective view of toilet rim blocks embodying the new design according to a second embodiment;

FIG. 10 is a bottom perspective view thereof;

FIG. 11 is a front view thereof;

FIG. 12 is a back view thereof;

FIG. 13 is a right-side view thereof;

FIG. 14 is a left-side view thereof;

FIG. 15 is a top view thereof; and,

FIG. 16 is a bottom view thereof.

The broken lines shown in the drawings depict portions of the toilet rim blocks that form no part of the claimed design.

1 Claim, 16 Drawing Sheets
